UNITED STATES PATENT OFFICE.

GUSTAV SCHUMANN, OF PHILADELPHIA, PENNSYLVANIA

IGNITION SYSTEM.

1,302,474.

Specification of Letters Patent. Patented Apr. 29, 1919.

Application filed December 22, 1916. Serial No. 138,483.

To all whom it may concern:

Be it known that I, GUSTAV SCHUMANN, a citizen of the United States of America, residing at 3104 Pennock street, Philadelphia, 5 in the county of Philadelphia and State of Pennsylvania, have invented new and useful Improvements in Ignition Systems, of which the following is a specification.

The object of this invention is to provide 10 an improved apparatus for successfully making and breaking an electrical circuit.

Another object thereof resides in an apparatus of the above character, operable for use in connection with the sparking system 15 of an internal combustion engine, wherein is embodied improved features of construction for insuring the successful operation of the apparatus regardless of its speed of operation and, also, to dispense with the services 20 of the usual manually controlled lever, hitherto commonly employed in devices analogous to the present invention.

Other objects of my improved timing apparatus reside in providing the same with 25 collapsible contact making wings which, when operating to close a circuit will be under the influence of spring pressure, which will operate to force the wings away from its circuit closing position, so that 30 when the means for operating the apparatus cease to revolve, it will be impossible for the electrical circuit, controlled by the timing apparatus, to remain closed; to provide improved circuit closing means comprising a 35 plurality of resilient arms, one of which carries a contact strip forming a part of an electrical circuit, said arms being arranged to directly contact with the rotatable wing members carried by a rotatable ele- 40 ment, the contacting of the wing members with the resilient contacting arms forms a distinct part of the present invention, inasmuch as it eliminates the use of intermediate motion transmitting members, simplifies the 45 construction of the device and promotes the successful operation.

Other objects will be in part obvious and in part pointed out hereinafter.

With these and other objects in view, the 50 invention consists in the features of construction, combination of elements and parts hereinafter set forth, illustrated in the accompanying drawings, and more particularly pointed out in the appended claims.

55 In the drawings

Figure 1 is a front elevation of the timing apparatus comprising present invention, illustrating the circuit closing members in an open position.

Fig. 2 is a similar view disclosing the circuit closing members in a closed position.

Fig. 3 is a side elevation, illustrating diagrammatically the electrical circuit employed in connection with the timing apparatus.

Fig. 4 is a top plan view.

Fig. 5 a detailed perspective view of the commutator and its associated wing elements.

Fig. 6 is a front elevation of a slightly 70 modified form of the timing apparatus comprising the present invention.

Fig. 7 is a top plan view of the modified form and

Fig. 8 is a detailed view disclosing a still 75 further modification.

Similar characters of reference denote corresponding parts throughout the several views of the drawings.

Although I am aware that various forms 80 of make and break devices have been used heretofore in connection with internal and other combustion engines and machinery, wherein it has been endeavored to produce an abrupt and instantaneous spark to make and break the electrical circuit, it has been found that actual tests do not bring about a uniform and non-increasing consumption of current regardless of the speed of operation 85 of the mechanism or machine forming the intermediary to bring about the desired result. In my device I provide a mechanical construction adapted to the making and breaking of a circuit whereby the amount of current consumed will be substantially uniform 90 regardless of the speed of rotation of the primary mechanism, and in which the closing of the circuit and the subsequent breaking of the same will be instantaneous 95 but positive, with a minimum consumption 100 of current.

In a great number of the known devices 105 rotatable members are employed, having radially extending pins or wings incapable of other movement than to turn with the rotatable element. Constructions of this nature do not insure the accurate making and breaking of the circuit with a minimum amount of current and further by having the wings or pins permanently arranged 110

upon the rotatable part, there is in time a certain amount of wear which would not take place if the pins were of a resilient or collapsible nature. Still further it is known 5 that in electrical contact devices there have been used pivotally mounted pins or wings upon the rotatable member, in order to effect the desired result. In these instances, however, the wings or pins are not strictly freely 10 movable, or collapsible as in the nature of a collapsible tap or other tool of a similar character. In my device I have the wings or pins so arranged that they are in every sense technically collapsible, and are freely movable 15 upon the rotatable member, aside from rotating with it as it turns about its axis.

The preferred embodiment of the timing apparatus, that is, the form illustrated in Figs. 1 to 5 of the drawings, comprises a 20 metallic base plate 1, having formed thereon an extended hub 2 in which is formed a central opening 3 for the reception of a drive shaft 4. This shaft when the device is employed in connection with an internal combustion engine, may be suitably driven by any of the rotatable elements of the engine, and is operable to rotate at a time speed, as will be clearly understood. The outer or 25 free extremity of the shaft 4 protrudes beyond the outer face of the base plate 1, and has keyed or otherwise secured thereto a circular wing carrying element, to be herein-after termed the rotatable element; said element being adapted to rotate in uniformity 30 with the shaft 4.

The element 5 preferably consists of circular plates 6 and 7, which are disposed in parallel relation and are united by a sleeve or bushing 8, the latter being provided with 40 a central keyed bore 9 for the reception of the protruding extremity of the shaft 4. Pins or studs pass transversely through the element 5 and are located at spaced intervals in order to pivotally receive wings or 45 fingers 11, said fingers or wings being generally located between the plates 6 and 7 of the element, and are adapted to freely oscillate about the trunnions 10, the swinging movement of the wings being limited or 50 defined by cross studs 12, which extend between the plates of the element. It will be noted that by the connection existing between the wings of the element, that said wings will be capable of responding to centrifugal force when the element is in a state of rotation, so that the outer beveled extremities 13 of the wings will extend to a position beyond the peripheral edges of the element, when the member 5 is rotating, so 55 that the wings will lie in radial relation with the element, and will be held in this position by the action of the studs 12. However, it will be noted that the wings are not obliged to always resume this extended position, as it will be noted that the 60

distance between the studs 12 is sufficient to permit the wings to oscillate to what will be hereinafter termed an inactive position within the element.

The wings 11 are adapted to control, that 70 is, open or close, an electrical circuit 15 which may embody an insulated terminal 16 which, as shown, is insulated as at 17 from the base plate 1. Connected with the terminal 16 by means of a hand nut or an equivalent 18, is one end 19 of the circuit 15, the lead 19 extends to the battery or other source of power 20, and thence to the usual primary coils 21. A lead 22 extends from the coils 21 to a second terminal 23 80 and is grounded upon the base plate 1. In connection with this circuit the invention provides improved means for establishing electrical communication between the plate 1 and the insulated terminal 16. 85

To this end use is made of resilient and flexible contact carrying arm 25, the latter being secured to a stationary post 26 fixed to the base plate 1. It will thus be evident that the outer end of the arm 25 90 may readily oscillate, and secured to the free end of the arm 25 is a contact disk 27 of platinum or other similar material. The disk 27 is nominally situated in spaced relation from an adjustable set screw 28, threaded to the binding post or insulated terminal 16, said set screw being adjustable, in order that the distance between the disk 27 and a similar disk 29, carried by the set screw 28, may be varied. 95

In order to establish electrical communication between the contact disks 27 and 29, the arm 25 has rigidly secured thereto an offset extension 30, which extends toward the element 5 and is provided with a cam 105 extremity 31, located contiguous to the element 5, so as to be in path of movement of the wings 11 when the latter are in a state of rotation. The extension 25 is also provided with a locking extremity 32 which 110 is designed to engage the free end of the resilient contact making arm 25, so as to prevent any undue vibration on part of the arm 25, which will probably result in closing the circuit 15, as will be readily 115 understood.

In order to insure the contacting of the arms or wings 11 with the cam projection 31 of the extension 30, I provide a trip arm 35, of similar construction with respect to the arm 25, the trip arm preferably consists of a flat resilient spring 36 having one extremity fixed as at 37 to a stationary post 38, the action of the spring being governed by stop pins 39. Secured to the spring 36 120 as at 40 is a trip extension 41, the latter being provided with a hooked extremity 42 which is adapted to extend to a point adjacent to the peripheral edge of the element 5. The trip arm is primarily used to pre- 125 130

vent the wings 11 from remaining in engagement with the contact carrying arm 25 and to also insure the coöperation of the wings with the arm 25.

5 In operation, upon the rotation of the element 5 the wings or fingers 11 carried thereby, will be forced to resume their active or extended positions by the action of centrifugal force, so that the beveled extremities thereof will lie beyond the peripheral edges of the element. When in this position the wings will, when revolving in direction of the arrow B, as shown in Fig. 1, engage with the hooked extremity 42 of the trip arm, this feature being insured by the location of the coöperating studs 12. The continued rotation of the wings results in their engagement with the cam extremity 31 of the contact carrying arm 25, so that the latter will be forced to oscillate and will carry therewith the contact disk 27 into engagement with the contact 29 of the set screw 28, so that the circuit 15 will be bridged. Now in order to insure a rapid breaking of the circuit 15, to establish a clear spark, the hooked extremity 42 of the trip arm will press upon the beveled end 13 of the wing or finger with which it is coöperating, and the influence of the spring-pressed trip arm will result in forcing the wing to collapse, that is, to swing away from the cam extension 31 and to thus permit the arm 25 to return to its normal position. A stud 45 is employed to regulate the arm 25 in this respect.

25 The cam extension 31 of the arm 25 also facilitates the collapsing of the wings or fingers 11.

From the foregoing it will be obvious that the action of the collapsible wings or fingers 11 will be extremely efficient and positive in operation and that their action will be directly imparted to the contact carrying arm, without employing the services of intermediate auxiliary motion transferring element, as hitherto in common practice. The elimination of mechanical "lag" is one of the results of this direct movement, and by this construction any explosive motor can be operated from 50 R. P. M. up to substantially 1000 R. P. M., without necessitating the use of manual spark advance levers, or automatic spark advancing devices, this being due to the fact that the sparking or firing increases in direct proportion to the advance of the motor's speed. Moreover, there are no possibilities of the contact points 27 and 29 ever remaining in a closed position, this being due to the expulsion force exerted upon the wings 11 by the trip arm 35, and will, therefore, disclose a marked depreciation in the quantity of current consumed thereby, over the devices of the prior art.

60 The wings will only operate when the element 5 is revolving in an anti-clockwise direction thus the possibilities of a motor

back-firing or kicking quotation will be eliminated. The current consumption as before stated, is unusually low, as current is only used when needed and for brief periods only, as it will be noted that the circuit 15 is 70 of the so-called open circuit type.

It is obvious that numerous changes may be made in the details of structure of the timing apparatus above described, and several of such changes or modifications have 75 been disclosed in Figs. 6 to 8 of the drawings. In Figs. 6 and 7 the timing apparatus consists of the base plate 1^a and a rotatable element 2^a, and which is driven by a revolving shaft 3^a. The pivoted wings 4^a are carried 80 by the element 2^a and are provided with beveled extremities 5^a. When the element is in a state of rotation the extremities 5^a of the wings lie beyond the peripheral edges of the element 2^a and when in this position 85 said beveled extremities will contact with the resilient trip arm 7^a, which is fixed to the base plate 1^a. A resilient contact carrying strip 8^a is also fixed to the base plate 1^a by means of a stud or an equivalent 9^a, said 90 contact carrying arm being provided with a hooked extremity 10^a, which is operable to engage with the substantial V-shaped extremity 11^a of the trip arm 7^a, thus when the trip arm engages with the wings 4^a the 95 same will be elevated and will carry in unison therewith a contact carrying arm 8^a, so that a contact point 12^a carried by the arm 8^a, will be forced to engage with a similar contact point 13^a, adjustable within an insulated 100 terminal or binding post 14^a, whereby an electrical circuit, not shown, will be completed. The V-shaped extension 11^a of the trip arm 7^a is of peculiar construction, so that when the wings 4^a pass from one side 105 to the other thereof, the wings will be forced or thrust away from its extended active position to a collapsed or inactive position, substantially in the manner accomplished in the preferred form.

110 In Fig. 8 a still further modification has been disclosed in which a trip arm 7^a is provided with a longitudinal extending slot 7^b, said slot being adapted to coöperate with the beveled extremities 5^a of the wings 4^a so that the oscillation of the flexible and resilient contact carrying arm 8^a may be readily controlled.

115 Thus it will be evident that the objects of the present invention have been achieved, 120 and that all of the advantageous features above mentioned are, among others, present. The device is simple in construction, of few parts, and not liable to become out of order, said parts being readily accessible so that in the event any of the same become disabled, the disordered part or parts may be readily removed or repaired, or a new part may be substituted in lieu thereof.

125 Attention is particularly called to the fact 130

that the wings are freely movable in every sense upon the rotatable element, the stop pins being provided merely for the purpose of limiting the free movement in a certain direction when the pins are in operating position. It is because of the freely movable wings that the rotatable member can be properly termed a collapsible cam or collapsible element, and the individual wings do not rely upon individual springs to retain them in operating positions; the wings moreover would assume their operating positions due to the centrifugal action of the rotatable member, and it is the spring action of the trip arm which is the unit for all of the wings as they move into operating position, whereby the tripping of the wings is accomplished so that they will successively operate to close the circuit at the particular moment when it is desired to release the spark.

It will be seen that at the particular moment when any one of the wings is in the position whereby it has moved the movable contact carrying member into engagement with the stationary contact member to close the circuit, that particular wing will be under the reverse pressure of the movable contact member and the trip arm, causing the wing to swing upon its pivot and collapse toward the axis of the rotatable member or cam. It may also be noted here that due to the particular construction and formation of the wings and their relation to the movable contact member, any one wing at the moment of contact with the movable contact member, causing the latter to close the circuit with the rigid contact member, will, by the reverse action of the spring of the movable contact member collapse to an inoperative position, permitting said wing to readily pass by the movable contact member, and thereby insure the breaking of the circuit as quickly and in as short a time as the circuit is closed by the action of the wings coming in contact with the movable contact member.

Therefore as mentioned heretofore the particular formation of the rotatable member or cam and its juxtaposed parts, namely the wings, will result in the making and breaking of a circuit in an instant of time and with a minimum amount of current, that is to say, regardless of the speed of rotation of the cam, the amount of current used in making and breaking the circuit will be uniform, and will not increase in proportion to the increase in speed.

In conclusion attention is directed to the directness of the method employed to close the circuit, and by which it will be seen the use of auxiliary or other motion transmitting devices is entirely obviated, to the end that the most simple and economical, but

positive and effective construction and operation is obtained.

Also, it will be observed that in Figs. 6 and 8 that the oscillating action of the springs 7^a will take place about pivotal points located on a plane beneath beveled extremities of the wings 5^a, so that when the wings are being discharged from engagement with the springs, the arcs upon which the springs oscillate will be such as to exert a direct force upon the wings in the approximate direction in which the latter are traveling. This arrangement of parts greatly facilitates the expulsion of the wings from engagement with the springs 7^a, as will be readily understood. Furthermore, the strength and action of the springs 7^a will be considerably enhanced by the method, disclosed in the modified forms, of mounting the same upon the base plate 1^a.

Having described the invention what is claimed as new and patentable is:

1. In a device of the character described, the combination with a spring actuated contact-making member, of a rotatable cam consisting of a rotatable element and freely movable wings thereon, the latter engaging the contact-making member to move the latter into contact-making position, the wings being then reengaged by the contact-making member so that the spring power of the latter will move the former out of operating position, when the cam is rotating.

2. In a device of the class described, the combination with a spring actuated contact-making member, of a cam consisting of a rotatable element, and freely movable members thereon, the latter being unhindered by any spring like action except when, in the rotation of the element said freely movable members engage the spring actuated contact making member, and are in turn operated upon by it, to move said members out of operating position.

3. In a device of the character described, in combination with a rotatable shaft, and an element rotatable with said shaft, oscillating wings carried by said element and provided with substantially beveled working extremities, resilient circuit closing members operable to engage with the beveled extremities of said wings, and adapted to have the securing and pivoted points thereof located substantially on a plane beneath the beveled extremities of said wings, when the latter are engaging with the resilient circuit closing members.

4. In an interrupter, the combination with circuit controlling mechanism comprising a resilient contact strip and a trip-arm normally engaging said strip; of a rotary element, swinging wings carried by the rotary element, and means also carried by the rotary element for limiting movement of the

- said wings, the wings being arranged to engage the trip-arm during rotation of the rotary element.
5. In an interrupter, the combination with circuit controlling mechanism comprising a resilient contact strip and a trip-arm normally engaging said strip; of a rotary element, spaced stops carried by said rotary element, and wings pivoted to the rotary element and movable between the stops and arranged to engage the trip arm of the circuit controlling mechanism during rotation of the rotary element.
6. In an interrupter, the combination with circuit controlling mechanism comprising a flexible arm carrying a contact strip and having means for limiting the vibration of said strip, and a trip-arm normally engag-
- ing the flexible arm; of a rotary element having swinging wings arranged to engage 20 the said trip-arm during rotation of the rotary element.
7. In an interrupter, circuit controlling mechanism actuatable by a rotary element and made up of a contact carrying arm having 25 a hook-like extremity on which is a cam extension and a rearwardly directed portion, a resilient contact strip carried by said arm and having its free end opposed to said rearwardly extending portion on the hook, and a resilient trip-arm normally engaging the cam extension on the first named arm and positioned to be first engaged by the rotary element.

In testimony whereof I affix my signature. 31
GUSTAV SCHUMANN.
